CABLE CODE SIGNALING SYSTEM

Marion H. Woodward, East Orange, N. J., assignor to International Communications Laboratories, Inc., Newark, N. J., a Corporation of New York

Application March 4, 1932. Serial No. 596,771

11 Claims. (Cl. 178—63)

This invention relates to improvements in cable code printers of the type disclosed in United States Letters Patent No. 1,895,095 issued to A. F. Connery and M. H. Woodward. The invention provides means for operating a ten-magnet cable code printer by circuits controlled through a counting relay bank.

One of the objects of the invention is to provide means for operating a telegraph printer directly by cable code signals. Closely connected with this feature of the invention is the operation of a telegraph printer by codes other than cable codes but composed of equal or unequal length letters.

A further object of this invention is to provide means whereby all of the impulses received are used to make a selection of a predetermined letter or number.

Further objects and the means for accomplishing them will be disclosed, or will be obvious to those versed in the art, upon reading the specification in conjunction with the accompanying drawing which is a schematic diagram of a circuit employed to accomplish the various objects of the invention.

In the ordinary five-selecting-magnet multiplex printer, five code bars, each controlled by one of the five selecting magnets, are provided. Each code bar has two positions, an operated position and an unoperated position. By proper selection, the five code bars may be positioned to obtain thirty-two possible permutations. However well this system of operation may be for land lines where two-element codes, namely, plus and minus element codes, are used, this type of printer is not directly applicable to cable code operation because the cable code is a three-element code consisting of plus, minus and zero elements.

This invention provides a novel method of operating the selector magnets of a printer from cable code signals. The longest letter in the cable code is five units. By adding another set of five selecting magnets and selecting bars to the printer, operation of the printer with cable code signals may be accomplished. The first set of bars may be made to operate from dots and the added set from dashes.

The actual connection of the dot and dash relays to the cable may be accomplished in any suitable manner, and, since this is well known in the art and forms no part of this invention, there is no need to describe it in detail.

A developed view of the distributor is shown in the drawing. Means for maintaining the dis-

tributor brushes in synchronism with cable signals is well known and is not shown or described, since it forms no part of the invention.

The arrangement of the apparatus is such that a dot in a cable code combination will cause the actuation of a selector magnet in one bank or set of magnets in the printer, thus positioning the code bar associated therewith, while a dash will cause the actuation of a selector magnet in another bank of magnets in the printer and, likewise, set the code bar associated with that magnet. Take, for example, the letter A. The cable code signal for the letter is dot, dash. The first unit of the letter A, being a dot, will operate the first code bar in the first or dot bank of magnets. The second unit of the letter A is a dash and will operate the second magnet in the second or dash bank of magnets and, thus, will operate the second code bar in the code bars associated with the second set of magnets.

The letter spaces are used to cause the operation of the printing functions of the printer, to print the letter previously selected by the ten selecting magnets. Since two sets of five bars are actually used, any one of sixty-two different selections may be obtained.

In the drawing, the set of five selecting magnets for the dot signals are numbered from 1 to 5, and the set of dash selecting magnets are numbered from 6 to 10. The first pulse in each letter will cause either magnet 1 or magnet 6 to be operated. Magnet 1 will be operated if the first pulse is a dot; magnet 6, if the first pulse is a dash. The second pulse in the letter will cause magnet 2 or magnet 7 to operate, depending upon the polarity of the signaling impulse. The third, fourth and fifth impulses will operate magnets 3, 4, 5 or 8, 9, 10, respectively, depending upon the polarity of the impulse.

A system of relays provides the means for counting the number of pulses in each letter, in order to determine which magnet is to be operated by each signal pulse. This is accomplished by a group of counting relays which operate in connection with the two input relays and the constant speed or synchronized distributor, which is maintained in synchronism with the sending transmitter by any one of a number of well known means.

In this system, it is necessary to distinguish between one zero interval, which represents a letter space, and three zero intervals, which represent a word space. The counting relay bank which is used for counting the dot and dash

signaling impulses is also used for counting the space intervals.

In this system a counting relay chain bank is used to determine which magnets in the printer are to be selected, as described below, and no perforated tape or other storing means are necessary.

A more detailed description of the apparatus will now be given.

As shown in the drawing, relays 28 and 29 are operated by the incoming signals. The tongue of relay 28 moves to its marking contact whenever either dots or dashes are received, and is on its spacing contact for spaces. Relay 29 moves its tongue to its marking contact when dots are received, and its tongue is spaced whenever dashes or spaces are being received. The tongue of relay 28 operates relay 30, whose tongues determine the endings of the various letters received over the cable. Tongue 43 causes the counting relays to be operated in the following manner:

For a letter three unit impulses in length, the incoming signal causes tongue 43 to move to its marking contact at a time when the brush on the distributor is midway between the A and B segments at the extreme left of the drawing.

A short time later the brushes revolving over the distributor ring in synchronism with the incoming signals reach the A segment, at which time a circuit is established from positive battery, through the A segment, through the tongue and spacing contact at 34, the winding of relay 31, through the marking contact and tongue at 43 to negative battery. Upon the completion of this circuit, contact 35 is closed and a circuit is conditioned for energization from positive battery, through the winding of relay 24, through contacts 35 and windings of relay 31 to negative battery, as before. However, while the brushes are on the A segment no current flows through winding 24, because this winding is short-circuited by the circuit through the A segment. When the brush passes off the A segment, the short-circuiting path is open and current then flows through winding 24 and winding 31 to negative battery and, thus, these relays are locked up. For the next impulse, when the brush again reaches an A segment, a circuit is then established from battery, through the second A segment, the tongue and marking contact at 34, the tongue and spacing contact at 36, the winding of relay 32 to negative battery through the tongue and marking contact at 43. In the same manner as already described, a circuit is then set up from positive battery, through the windings of relay 25, contacts 37, the winding of relay 32 to negative battery. No current, however, flows in this circuit until the brush passes off the second A segment, at which time current flows through the windings of relay 25, contacts 37 and winding of relay 32, to negative battery, thus operating relay 25 and locking up relay 32. For the third impulse, the brushes again reach an A segment and a circuit is then established from battery, through the third A segment, through the tongue and marking contacts at 34, through the tongue and marking contacts at 36, through the tongue and spacing contacts at 38, through relay 33 to negative battery, through the tongue and marking contact at 43.

As before, a circuit is set up from battery, through relay 26 and contacts 39 and relay 33, to negative battery, but no current flows until the brush passes from the third A segment. At

this time relay 26 is operated and relay 33 is locked up. At the conclusion of the three impulses, the tongue at 43 moves from its marking contact to its spacing contact. During the transition time, the locking circuits through windings 31, 32 and 33 are open, and these relays and relays 24, 25 and 26 are restored to their normal positions. Thus, these relays count the number of impulses in any particular signal combination. For spaces, the tongue at 43 is on its spacing contact and the counting relays operate in the same direction and are unlocked during the transition time from spacing to marking. Relays 24, 25, 26 and 27 have other contacts which are associated with the selecting magnets of the printer. Whenever dots are received, a circuit is established from battery through the B segment, tongue and marking contact at 44, tongue and marking contact of relay 29, through contacts 11, 12, 13 and 14, as the case may be, to operate selecting magnets 1, 2, 3, 4 or 5. Whenever dashes are to be received, a circuit is established from positive battery, through the B segment, tongue and marking contact at 44, tongue and spacing contact of relay 29, through contacts 15, 16, 17 or 18, to operate selecting magnets 6, 7, 8, 9 or 10. Whenever spaces are to be received for the first space, or letter space, a circuit is established from positive battery, through the B segment, through the tongue and spacing contact at 44, through the tongue and spacing contact at 19, to operate the printing magnet 42 in the printer. The second space indicates a word space and the circuit is then further completed through the tongue and spacing contact at 44, through the tongue and marking contact at 19, through the tongue and spacing contact at 20, through the fourth selecting magnet which selects a word space. The third space is, therefore, completed through the tongue and marking contact at 20, the tongue and spacing contact at 21, to the printing magnet 42 for printing the word space.

Selecting magnets 1 to 10 are thus operated whenever their corresponding signals are received, that is, when the counting relays have counted a sufficient number of impulses. Thus, for the letter "F", which consists of a dot, dot, dash, dot, the first impulse operates the selecting magnet 1 through the tongue and spacing contact of 11. The second impulse operates the selecting magnet 2 through the tongue and spacing contact at 12, the third impulse operates selecting magnet 8 through the tongue and spacing contact at 17, and the fourth impulse operates the selecting magnet 4 through the tongue and spacing contact at 14.

Whenever a signal has five impulses, the character to be printed will be in the upper case. This is accomplished by a circuit through the B segment, the tongue and marking contact at 44, through the contacts at 22 to the shift magnet 41. Contacts 22 are closed for the fifth impulse. The printer is restored to the lower case mechanically whenever a word space is received.

The letter space at the end of each letter causes relay 28 to space, thereby de-energizing relay 30. This causes the circuits leading to the counting relays to be broken at tongue 43, whereupon the counting relays all go to spacing. Since tongue 44 also goes to spacing position simultaneously with tongue 43, the B segment of the next pair of segments completes a circuit from positive battery, the afore-mentioned B segment, the spacing contact of tongue 44, the spacing con-

tact of tongue 19 to energize printing magnet 42, whereupon the selected letter or number is printed.

This description of the operation of the apparatus is given as one embodiment of the invention. It is not intended to limit the scope of the invention, which is defined in the appended claims.

What is claimed is:

10 1. In a telegraph system, means for receiving signals composed of a non-uniform number of equal length impulses, recording means having a plurality of sets of selectable printer magnets, and means for operating the magnets of said sets in different combinations from the received signals.

15 2. In a telegraph system, means for receiving signals composed of a non-uniform number of equal length impulses, recording means having a plurality of sets of selectable printer magnets, and means for operating the magnets of said sets in accordance with the sequence of the impulses making up any particular signal.

20 3. In a telegraph system wherein signals of non-uniform duration composed of equal length elements are transmitted, signal recording means comprising a printing device having a plurality of sets of printer magnets, and means for controlling the operation of the magnets of said sets 25 in an order determined by the order of the impulses in a received signal.

25 4. In a telegraph system, means for receiving signals having a non-uniform number of uniform length impulses of various polarity, a receiving device comprising a printer and sets of selectors therefor, each of said sets having a plurality of selectable printer magnets, and means for operating said printer magnets according to received signals.

30 5. In a telegraph system, means for receiving signals composed of a non-uniform number of uniform length impulses, recording means having a plurality of sets of selectable printer magnets, and means for operating the magnets of said sets 35 in different combinations from the received signals, each impulse of said signal causing the operation of at least one magnet in said sets.

35 6. In a telegraph system, means for receiving signals composed of a non-uniform number of uniform length impulses, recording means having a plurality of sets of selectable printer magnets, and means for operating the magnets of said sets 40 in different combinations from the received signals, each impulse of said signal causing the operation of at least one magnet in said sets.

45 7. In a telegraph system, the combination of means for receiving signals in a code having letters of unequal length composed of equal length elements, a plurality of sets of selector magnets operable by signal combinations in said code, and relay means responsive to said signals to divert signals of the same polarity to the same set of selector magnets.

causing the operation of at least one magnet in said sets in a predetermined order.

5 8. In a telegraph system, the combination of means for receiving signals in a code having letters of unequal length composed of equal length elements, a plurality of sets of selector magnets operable by signal combinations in said code, and relay means responsive to said signals to divert signals of the same polarity to the same set of selector magnets.

80 8. The method of operating a telegraph printer from a code having characters formed of unequal numbers of equal length impulses of different kinds, which comprises operating one set of selecting mechanisms of said printer by impulses of one kind, operating another set of selecting mechanisms of said printer by impulses of another kind, diverting said impulses to the corresponding set of selecting mechanisms by operating a group of relays, and thereafter initiating the printing operation of said printer by impulses of a third kind.

85 9. In a telegraph system wherein signals composed of uniform length elements of positive, negative and zero polarity are employed, relay means for receiving said signals, a distributor co-operating with said relay means to control recording means comprising a telegraph printer having two sets of selecting mechanisms, the mechanisms in one of said sets being selectively operated by the elements of positive polarity while the mechanisms in the other of said sets are selectively operated by the elements of negative polarity.

90 10. In a telegraph system wherein signals composed of equal length elements of positive, negative and zero polarity are employed, relay means for receiving said signals, a distributor co-operating with said relay means to control recording means comprising a telegraph printer having two sets of selecting mechanisms, said mechanisms being selectively operable by signals composed of positive and negative polarity elements.

95 11. In a telegraph system wherein the signals transmitted are composed of a varying number of different kinds of uniform length elements, a plurality of sets of selecting mechanisms, each of said sets being operable by one kind of element only, a shift mechanism operated by signals of a predetermined length, and means for printing a character corresponding to said transmitted signals and the positions of said shift mechanism.
